YARN AND FABRIC MADE THEREFROM

Ralph C. Anderson, Charlotte, N. C.

Application February 26, 1936, Serial No. 65,861

5 Claims. (Cl. 117—2)

This invention relates to a yarn and to a fabric produced therefrom and more especially to a twisted yarn having a cotton strand and an acetate strand twisted together with the acetate strand having intermittently spaced portions thereof saponified so as to have an affinity for a cotton dye, leaving the untreated portions without an affinity for the cotton dye but retaining an affinity for an acetate dye so that the yarn can be used in circular knitting machines for the knitting of stockings and especially the tops of stockings to produce pattern effects therein when the stocking is dyed.

It is an object of this invention to provide a yarn having a cotton strand and an acetate strand twisted together with intermittently spaced portions of the acetate strand being previously saponified before being twisted with the cotton strand to provide a yarn having cross dyeing capabilities for the production of pattern effects in knitted fabrics.

It is another object of this invention to provide a yarn comprising two strands twisted together with one of the strands having an affinity for a certain dye and with intermittently spaced portions of the other strand having an affinity for the said certain dye while the other portions of said other strand do not have an affinity for said certain dyes but for a different type of dye.

It is another object of this invention to provide a pattern effect in a knitted fabric such as the top of a stocking by means of twisting two strands together to form a yarn, said strands being of different materials and one strand having intermittently disposed portions thereof treated to render it subject to be dyed with the same dye which is used for dyeing the other strand so that a twisted strand can be produced having intermittently spaced portions thereof subject to one type of dye while one of the strands in the other intermittently spaced portion will have an affinity for another type of dye so that the yarn can be knitted into a stocking and the stocking cross dyed to produce the desired pattern effects.

Some of the objects of the invention having been stated, other objects will appear as the description proceeds when taken in connection with the accompanying drawing, in which:—

Figure 1 shows a stocking knitted from my new type of yarn;

Figure 2 is a developed view of the upper portion of Figure 1;

Figure 3 is an enlarged detailed view of a portion of the yarn;

Figure 4 is an enlarged detailed view of a por-

tion of the knitting in the upper part of the stocking shown in Figures 1 and 2.

In preparing this yarn, I take an ordinary twister frame and twist two strands together therein. One of these strands, let us say, is represented by reference character 10 and is a cotton strand. The other strand 11, for example, may be an acetate strand. Portions 12 of the strand 11 are saponified so that these portions have an affinity for a cotton dye. The other portions 12a of the acetate yarn are not saponified and therefore do not have an affinity for a cotton dye.

Referring to Figure 3, it is there shown where the portion 15 is composed of the cotton strand and the saponified portion 12 of the acetate 15 strand twisted together. The portion 16 is the cotton strand and an unsaponified portion of the acetate strand twisted together, whereas, portion 17 of the yarn is similar to 15 and comprises another portion of the saponified acetate and the cotton yarn twisted together. The length of the saponified portions can be as desired, but I can produce a very good pattern effect by having the lengths of saponified sections sufficient so that in the twisted yarn a spot of the saponified 25 and unsaponified portions will be long enough in a circular knitting machine knitting a particular size of stocking, to furnish enough yarn in a particular portion to knit three-fourths the way around the stocking or three-fourths of a 30 course. This makes a spiral stripe around the stocking.

Let us suppose that the portions 17, which are treated would dye black, whereas, the unsaponified length 11 of portion 16 would remain white. 35 Therefore, we can see that in knitting the ribbed top 18 of a stocking, the portion 16a in Figure 2 would go three-fourths the way around the stocking to the point a, and then the portions 17a of the treated yarn would begin and continue 40 another three-fourths the way around the stocking to the point b, and then another portion 16b would begin and go three-fourths the way around the stocking to point d, and then another portion 17b would begin and go to the point c, or 45 three-fourths around the stocking and this would continue throughout the knitting.

This would produce a spiral stripe around the top portion of the stocking due to the saponified and unsaponified portions of the yarn being susceptible to different dyes, and whereby cross-dyeing could be carried out either in the finished stocking or in the yarn before knitting.

Of course, it is evident that other desired pattern effects or stripe effects can be produced but 55

the above is an illustration where, for example, if it should take thirty-six inches of yarn to knit a complete course, then the portions of the yarn having a saponified section and a cotton section 5 in association, would be approximately twenty-seven inches long to produce three-fourths of a course of knitting.

It is evident that the sections of the saponified yarn in combination with the cotton yarn 10 could be varied as to length as well as the proportionate relation between the unsaponified sections and the saponified sections to produce the desired results.

In the drawing and specification there has been 15 set forth a preferred embodiment of the invention, and although specific terms are employed, they are used in a generic and descriptive sense only, and not for purposes of limitation, the scope of the invention being set forth in the appended 20 claims.

I claim:

1. That method of making stockings which comprises making a knitting yarn having alternately disposed portions of the yarn saponified 25 to be subject to a dye which will not dye the unsaponified portions, determining the length of the saponified portions so that a saponified portion will knit more than one-half of a course and the unsaponified portions will knit a portion of a 30 course equal in length to the portion of a course knitted by a saponified portion, so that when the knitted stocking is dyed a spiral striped effect is produced by the overlapping of the saponified and unsaponified portions.
- 35 2. That method of producing a stocking which comprises spinning a cotton strand, then saponifying alternately disposed portions of an

acetate strand, then twisting the two strands together, the saponified portions having a length which is equal to the length of the unsaponified portions, each portion being sufficient to knit more than half a course in a stocking, then 5 cross-dyeing the stocking to produce a striped effect.

3. That method of knitting a stocking which comprises preparing an acetate yarn having alternately disposed saponified and unsaponified 10 portions of equal length, a saponified portion and an unsaponified portion being sufficient to knit more than one complete course so that when the stocking is dyed a striped effect is produced in the stocking due to the overlapping of the 15 saponified and unsaponified portions.

4. A circular knit fabric knitted from a yarn which has been previously treated to cause alternately disposed contiguous portions of equal 20 length to have an affinity for two different dyes, a pair of said contiguous portions having a total length which is greater than the length of a course in said fabric whereby the overlap of said portions in the knitted fabric, when the same is cross-dyed, will produce a striped effect in the 25 fabric.

5. A circular knitted fabric knitted from an acetate yarn having alternatively disposed portions thereof saponified, the saponified and unsaponified portions being of equal length and being proportional in length to the circumference of the 30 knitted fabric, each portion being long enough to knit more than half a course to thereby produce a striped effect in the fabric when same is subjected to a dyeing operation.

RALPH C. ANDERSON.
